UNITED STATES PATENT OFFICE

136,163

DESIGN FOR A DOLL

Bessie E. Marek, Berwyn, Ill.

Application March 24, 1943, Serial No. 109,809

Term of patent 3½ years

To all whom it may concern:

Be it known that I, Bessie E. Marek, a citizen of the United States and residing in Berwyn, in the county of Cook and State of Illinois, have invented a new, original, and ornamental Design for a Doll, of which the following is the specification, reference being had to the accompanying drawing, forming a part thereof.

On the drawing:

Fig. 1 is a front elevational view of a doll, showing my new design; and

Fig. 2 is a side elevational view thereof.

I claim:

The ornamental design for a doll, substantially as shown.

BESSIE E. MAREK.
